208,982

COMBINED ELECTRICAL SWITCH AND TERMINAL SOCKET

Dudley H. Campbell, St. Marys, Pa., assignor to Stackpole Carbon Company, St. Marys, Pa., a corporation of Pennsylvania

Filed Jan. 14, 1966, Ser. No. 614

Term of patent 14 years

(Cl. D26—13)

Fig. 1

Des. 208,982

PAGE 2

FIG. 1 is an isometric view of the combined electrical switch and terminal socket embodying my design;

FIG. 2 is a plan view thereof;

FIG. 3 is a bottom view;

FIG. 4 is a view of the right-hand side of the switch as seen in FIG. 2; and

FIG. 5 is a view of the opposite side of the switch, but taken on an angle as indicated by line V-V of FIG. 2.

I claim:

The ornamental design for a combined electrical switch and terminal socket, as shown.
